US0D1012613S

(12) **United States Design Patent** (10) **Patent No.:** **US D1,012,613 S**
Tu (45) **Date of Patent:** **** Jan. 30, 2024**

(54) **BLADE HOLDER**

(71) Applicant: **SharkNinja Operating LLC**,
Needham, MA (US)
(72) Inventor: **Joyce Chien Tu**, Melrose, MA (US)
(73) Assignee: **SHARKNINJA OPERATING LLC**,
Needham, MA (US)
(**) Term: **15 Years**
(21) Appl. No.: **29/873,283**
(22) Filed: **Mar. 29, 2023**

Related U.S. Application Data

(62) Division of application No. 29/755,759, filed on Oct. 22, 2020, now Pat. No. Des. 982,971.

CLAIM

The ornamental design for a blade holder, as shown and described.

DESCRIPTION

FIG. 1 is a perspective view of a blade holder showing my new design;

FIG. 2 is a front elevation view thereof;

FIG. 3 is a rear elevation view thereof;

FIG. 4 is a side elevation view thereof;

FIG. 5 is another side elevation view thereof;

FIG. 6 is a top plan view thereof; and,

FIG. 7 is a bottom plan view thereof.

The broken lines in the drawings depict portions of the blade holder that form no part of the claimed design.
